Allen Xue(57) **CLAIM**I claim, the ornamental design for display screen or portion
thereof with graphical user interface, as shown and described.

DESCRIPTION

FIG. 1 is a front view of a display screen or portion thereof
with graphical user interface showing my new design; and,
FIG. 2 is a front view of a second embodiment thereof.
The broken line showing a display screen in both views forms
no part of the claimed design.**1 Claim, 2 Drawing Sheets**FIG. 1
